CLAIM

The ornamental design for a night light, as shown and described.

DESCRIPTION

FIG. 1 is a left side elevational view of a night light comprising the new design;

FIG. 2 is a front elevational view;

FIG. 3 is a right side elevational view;

FIG. 4 is a rear elevational view;

FIG. 5 is a top view;

FIG. 6 is a bottom view; and,

FIG. 7 is a front perspective view.

The broken lines included in the drawings are for illustrative purposes and form no part of the claimed design.
